UNITED STATES PATENT OFFICE

99,787

DESIGN FOR AN ELECTRICAL CONNECTER BODY

Charles E. Gilbert, New York, N. Y.

Application February 20, 1936, Serial No. 61,257

Term of patent 7 years

To all whom it may concern:

Be it known that I, Charles E. Gilbert, a citizen of the United States, residing at New York city, in the county and State of New York, have invented a new, original, and ornamental Design for Electrical Connecter Bodies, of which the following is a specification, reference being had to the accompanying drawing, forming part thereof.

In the drawing

Figure 1 is a plan view; and
Fig. 2 is a side elevation of the connecter showing my new design.

I claim:

The ornamental design for an electrical connecter body, substantially as shown.

In testimony whereof I have hereunto set my hand on this 18th day of February, 1936.

CHARLES E. GILBERT.
